F. McF. BRINCKERHOFF

SAFETY DEVICE FOR ARTICULATED CARS

Filed May 2, 1927

UNITED STATES PATENT OFFICE.

FRANCIS McF. BEINCKERHOFF, OF SUFFERN, NEW YORK, ASSIGNOR TO PRESSED STEEL CAR COMPANY, OF PITTSBURGH, PENNSYLVANIA, A CORPORATION OF NEW JERSEY.

SAFETY DEVICE FOR ARTICULATED CARS.

Application filed May 2, 1927. Serial No. 188,118.

This invention relates to transportation cars, particularly railway transportation cars of the articulated unit type, in which the adjacent ends of two of the bodies of the car are supported upon one truck, and has for an object the provision of means for preventing accidental excessive movement of one of said bodies relative to the other, and for preventing accidental excessive upward movement of one of said ends relative to the other and to the truck, and will thus prevent the accidental separation of said bodies and will tend to maintain both of said ends in connected relation with the truck.

Another object of the invention is to provide a member having its ends connected together by removable means to form a loop adapted to cooperate with two adjacent bodies of an articulated car unit to prevent accidental separation of said bodies.

These and other objects will be apparent from the following description.

Referring to the drawing in which like reference characters refer to like parts, Fig. 1 is a plan view of a portion of a railway articulated car embodying the invention, a portion of the view being broken away to more clearly illustrate the invention; Fig. 2 is a sectional view of the same taken on the line 2—2 of Fig. 1.

Referring now in detail to the drawing, the reference character 1 indicates one of the end portions of one body of a railway articulated car unit and 2 indicates one of the end portions of an adjacent body of the car unit, it being understood that the car may comprise two or any other desired number of bodies, and that the connection between any two adjacent bodies is substantially the same as hereinafter fully described.

Depending downwardly from the end portion 1 there is a bearing member 3 having a bearing surface 4 in the shape of a portion of a sphere, and depending downwardly from the end portion 2 of the adjacent body there is a like member 3. The bearing surfaces 4 cooperate with a bearing surface 5 formed on a bearing member 6 on an adjacent truck 7. These bearing members forming a connection between the bodies and truck and described in detail in my pending application for U. S. Patent Ser. No. 176,864, filed March 21, 1927, for articulated car.

Around the outer portion of the bearing surface 5, the bearing member 6 has an upwardly extending flange 8 which is adapted to be engaged by the bearing portions 3, and by such engagement under normal conditions, the bodies are held against excessive longitudinal or sidewise movement. In the case of a collision or derailment the flange 8 may become broken so that one car body may become separated from the adjacent body or one or both bodies may become separated from the truck and from each other, and to prevent this, I provide a loop 9 which cooperates with two adjacent bodies of the car unit in such a manner that the bodies will not be permitted to become separated from each other. In the present embodiment of the invention this loop 9 preferably comprises a metallic cable 10, the ends of which are connected together by a bolt 11 which may be removed when it is desired to mount the loop in its proper operative position on the car bodies or when it is desired to remove the loop from said bodies. This loop passes around the adjacent bearing portions 3 of both car bodies and is supported upon horizontally disposed brackets 12, which brackets are preferably integral with curved webs or stops 13 which depend downwardly from the end portions of both of the car bodies. By the use of the bolt 11 for securing the ends of the loop together, it will be seen that these ends, by the removal of the bolt, are readily disconnected and the cable can be removed from the car bodies. This form of loop member renders it possible to apply or remove the loop from integral brackets 12 on both car bodies. It will be noted that when the loop member 9 is mounted on the adjacent ends of two car bodies that there is a clearance provided between the loop 9 and stops 13 which is for the purpose of permitting the bodies to swivel without any binding action taking place between the loop member and the stops 13.

Under ordinary service conditions the loop 9 rests loosely on the brackets 12, thus permitting relative movement between the loop member and the brackets 12. Should a car equipped with the invention be derailed, the center bearing portions of the two adjacent bodies may become separated from the truck bearing member, but the bodies

will not become separated from each other due to the loop 9 engaging the stops 13 on the bodies. Should one body move accidentally an excessive distance relative to the other, the loop member 9 will engage the stops 13 and the brackets 12, and as the loop member is thus in engagement with both bodies, further movement is retarded by the weight of the body that is not moved, thus the bearing portions of the bodies are kept from becoming separated from the truck bearing. It will be noted that when the end portions of the loop member 9 are secured together, what is in effect a continuous loop is formed and when applied to the adjacent ends of two car bodies it is free to move relative to both of the bodies and has the advantage over an endless loop of being adapted to have its ends separated for easy removal or replacement.

Having thus described the invention what I claim as new and desire to secure by Letters Patent is:

1. A device for preventing the separation of the adjacent ends of two bodies of an articulated car comprising a flexible member having its ends connected to form a loop, the connection between said ends being separable.

2. In an articulated car comprising a plurality of car bodies, a stop on the end portion of each of said bodies, brackets on said stops extending outwardly therefrom, a loop member extending around said stops and loosely mounted on said brackets, and removable means for connecting the ends of said loop member to form a loop.

3. In an articulated car comprising a plurality of car bodies, downwardly depending stops on the end portions of adjacent car bodies, a loop member passing around said stops, brackets on said stops adapted to prevent movement of said loop member, and removable means connecting the ends of said loop member.

4. In an articulated car comprising a plurality of car bodies, downwardly depending stops on the end portions of adjacent car bodies, horizontally disposed brackets on said stops, a loop member extending around said stops and loosely mounted on said brackets, said brackets extending beyond said loop member, and means whereby the ends of said loop member may be disconnected to remove said member from said brackets.

In testimony whereof I affix my signature.
FRANCIS McF. BRINCKERHOFF.
